UNITED STATES PATENT OFFICE

123,985

DESIGN FOR A SEWING MACHINE

Anthony Sardu, Brooklyn, N. Y.

Application May 20, 1940, Serial No. 92,484

Term of patent 14 years

To all whom it may concern:

Be it known that I, Anthony Sardu, a subject of the King of Italy, residing in Brooklyn, county of Kings, and State of New York, have invented a new, original, and ornamental Design for a Sewing Machine, of which the following is a specification, reference being had to the accompanying drawing, forming part thereof.

The dotted line representation of a portion of the sewing machine has been omitted from Figs. 2 and 3.

The opposite side and end of the sewing machine frame is substantially the same as that shown in Figure 1.

I claim:

The ornamental design for a sewing machine, as shown and described.

This application is a continuation-in-part of my copending design application Ser. No. D-89,922, filed Feb. 1, 1940.

ANTHONY SARDU.
